1 Claim

ABSTRACT OF THE DISCLOSURE

An apparatus for guiding the leading end of an advancing strip emerging from a mill roll stand. A strip guide actuated by the raising and lowering of strip tensioning means prevents damage to the moving strip by contact with the guide.

Background of the invention

This invention relates generally to strip guides for rolling mills and more particularly to apparatus adapted to automatically adjust to varying conditions of strip tension.

In hot strip mills guides are placed at the exit side of the mill stands to guide the leading edge of an advancing strip toward the next stand. The leading edge has a tendency to turn up and if not properly guided will cobble due to the head end turning back and entering the mill doubled, thus fouling the mill rolls. Conventional strip guides comprise a plurality of flat plates or bars with one end resting directly on the work roll a short distance from the pass line and the other end engaging a rest bar between the mill housings. Counterweights attached to each guide plate maintain constant pressure of the guide plate against the work roll. The loosely mounted guide plates and counterweights have proven objectionable since frequently serious and costly wrecks have occurred when the guides were knocked out by the moving strip and run into the next stand. Furthermore, the frequent removing and replacing of the many parts of this apparatus to permit the changing of the work rolls is both costly and time consuming. The most important defect of the conventional guides, however, is the damage by scratching of the strip surface when the strip contacts the guide as a result of raising the strip pass line in the strip tensioning operation.

Summary of the invention

It is an object of this invention to provide a self-adjusting strip guide of simple construction which is readily moved in and out of its normal operating position.

The instant invention provides apparatus for guiding the leading edge of an advancing strip emerging from a mill roll stand comprising a single guide plate which is adapted to automatically adjust its position with respect to the surface of the strip and is so constructed as to be easily withdrawn from the work rolls sufficiently to allow roll changes in the mill without the necessity of removing the guide therefrom.

Brief description of the drawings

FIGURE 1 is a plan view of the strip guiding apparatus; FIGURE 2 is a vertical section of the apparatus of FIGURE 1, taken on line 2—2; and

FIGURE 3 is a sectional view similar to FIGURE 2 showing the apparatus withdrawn to the roll changing position.

Description of the preferred embodiment

Referring now to the drawings and particularly to FIGS. 1 and 2, the mill roll stand 10 is seen to comprise backup rolls 11 and work rolls 12 mounted between housings 13. A strip tensioning device mounted adjacent

2

to the exit side of mill roll stand 10, comprises looper table 15 which is rotatable about shaft 17. Looper roll 16 is mounted in bearings 19 at the ends of arms 14 for rotation about shaft 17. Cam 18 is fixed on the housing of the looper roll bearing 19 at one end of looper table 15 as e.g., by welding, for rotation with looper table 15.

Guide plate 20, which forms the strip guide, extends substantially the full width of work rolls 12. Lever arm 21 is removably attached to the center of guide plate 20 by insertion of one end of the lever arm into a short length of pipe sleeve 22 welded to the guide plate. A hole drilled transversely through the pipe sleeve 22 and lever arm 21 provides means for attaching the lever arm to the guide plate as by bolt 23. Lever arm 21 extends in the direction of the line of travel of the strip 30 and is substantially parallel thereto, although, because of the eccentricity of the cam surface, it is inclined slightly, and extends to a position where the other end of the lever arm rests in contact with the peripheral surface of cam 18. A slot or groove 24 is provided at the end of lever arm 21 to form a guide-way for the surface of cam 18. The actuation of the strip tensioning device or looper table 15 which is adapted to raise or lower looper roll 16 to tension the strip 30 will also cause the cam 18 to raise and lower thereby raising and lowering the strip guide plate 20 with respect to the surface of the strip 30 to avoid contact between the guide plate 20 and the moving strip 30.

The pivotal mounting of the guide plate 20 on the mill roll stand 10 comprises two spring elements 25, mounted on cylindrical pins 26 which project from the inside face of housings 13, the suitably formed ends 28 of the spring elements 25 being engaged with connecting elements 27 secured to the guide plate 20. The other end 29 of the spring elements 25 is removably engaged under a lug 31 attached to the inside face of the housings 13. It is clearly seen in FIG. 2 that this arrangement causes the guide plate to be biased against the work roll surface when the guide is in either the normal operating position, as shown in phantom, or raised position.

Referring now to FIG. 3 the strip guiding apparatus is seen to be in a position which allows easy removal of work rolls 12 when their changing is necessary. Manual removal of the spring end 29 from engagement with lug 31 and rotation about pins 26 will withdraw the guide plate 20 sufficiently for work roll changing to proceed without the necessity of completely removing the strip guide apparatus from the mill roll stand. The time consumed in preparing the mill for the next rolling will understandably be minimized.

In operation: The leading edge of a strip 30 emerging from the work rolls of a mill roll stand 10, having a tendency to curl upward, is deflected by strip guide plate 20 which is substantially horizontal when the threading of strip 30 is begun. The strip guide apparatus is held firmly in place by the engagement of cam 18 in slot 24 of lever arm 21 and the force of the torsion spring elements 25 which bias the guide plate against the work roll surface. The leading edge of the strip is fed into the next roll stand and the looper table 15 is actuated to raise up against the strip 30 to produce tension in the strip whereupon cam 18 engaging lever arm 21 causes the lever arm to raise also, thus lifting the guide plate to a position slightly inclined to the surface of the advancing strip. Contact of the strip surface with the strip guide plate which would otherwise result when the looper roll is raised is thus avoided and damage to the strip in the form of surface scratches is eliminated.

The guide apparatus is left attached to the mill stand during a work roll changing operation but is withdrawn out of the way by manually disengaging the spring end 29 from lug 31 to allow free rotation of the spring about pins 26. Rotation of the spring withdraws the guide plate

to a position sufficiently clear of the mill stand to avoid interference with the work roll changing.

It is thus seen that a unique and novel means for automatically moving a strip guide plate out of the way of an advancing strip is provided by the instant invention. The instant invention also provides an improved, inexpensive strip guide of simple construction which is easily maintained.

I claim:

1. In a strip guiding apparatus for a rolling mill, including a mill roll stand, a guide plate pivotally mounted on said mill roll stand and extending the width of the mill rolls, means to bias said guide plate against one of the work rolls, and strip tensioning means, the improvement comprising:

- (a) a lever arm attached to said guide plate and extending in the direction of the line of travel of said strip, and
- (b) a cam surface mounted on said strip tensioning means adapted to engage said lever arm to bias said

lever arm away from strip passing through the mill roll stand and over the tensioning means.
